The ornamental design for an end piece for a paper roll holder, as shown and described.

DESCRIPTION

FIG. 1 is a perspective view of the end piece for a paper roll holder, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top elevation view thereof; and,

FIG. 7 is a bottom elevation view thereof.

The dashed lines show a paper roll holder to provide context to the end piece for a paper roll holder, the dashed lines form no part of the claimed design.
